THE NORRIS PETERS CO., PHOTO-LITHO., WASHINGTON, D. C.

UNITED STATES PATENT OFFICE.

EMANUEL D. SCHMUCKER, OF AYR, INDIANA.

WIND-MOTOR.

SPECIFICATION forming part of Letters Patent No. 600,893, dated March 22, 1898.

Application filed July 9, 1897. Serial No. 643,965. (No model.)

To all whom it may concern:

Be it known that I, EMANUEL D. SCHMUCKER, a citizen of the United States, residing at Ayr, in the county of Marshall and State of Indiana, have invented certain new and useful Improvements in Wind-Motors; and I do hereby declare the following to be a full, clear, and exact description of the invention, such as will enable others skilled in the art to which it appertains to make and use the same.

My invention relates to an improvement in wind-motors; and it consists in a suitable supporting-frame, a wheel journaled therein, and a casing composed of two parts which are applied to opposite sides of the wheel and around which they revolve, combined with an upright which extends above the frame, a vane pivoted to the upright, a sliding collar placed upon the vane, and a curved rod which passes through an eye on the vane and by means of which the vane is moved into and out of the wind, as will be more fully described hereinafter.

The objects of my invention are to provide a motor which is operated by the wind and which can be started and stopped at the will of the operator and to construct a motor which is cheap and simple in construction, readily controlled, and which will not easily get out of repair.

Figure 1 is a perspective view of a motor which embodies my invention complete. Figs. 2 and 3 are plan views of the motor, showing the relative positions of the casing in relation to the rudder when the same is running and when at a standstill. Figs. 4, 5, and 6 are detail views showing the rudder and the parts connected therewith.

L represents a suitable framework, in which the wheel A is mounted vertically in the usual manner. Used in connection with this wheel is the casing B, which consists of the two vertical rounded portions, which are placed diametrically opposite each other upon opposite edges of the wheel. These two curved portions B are connected by cross-pieces, as shown, so as to be braced rigidly in relation to each other, and which parts can be adjusted in relation to the wheel in the usual manner for the purpose of throwing the wheel in and out of the wind. The lower end of the axle O of the wheel passes vertically through a

horizontal support N, which extends across in the frame L, while the upper end of the axle enters the lower end of the upright C, which extends a suitable distance above the top of the frame L and forms a support for the vane D.

The vane D is hinged in any suitable manner to the upright C, as shown in Figs. 4 and 6, and is provided with an eye G at any suitable point, through which the rod F passes. To the lower end of this rod F, which is curved or bent, as shown, is rigidly secured the sleeve E, which is splined upon the upright, so as to have a free rising-and-falling movement thereon. The collar H is loosely swiveled on this sleeve E, and to the collar H one end of the pivoted lever I is loosely connected, and by means of this lever the sleeve can be freely raised and lowered upon the upright C, no matter in what position it may have been turned by the upright C and vane D. As the sleeve E is raised the curved rod F is forced endwise through the eye G and is thus made to force the vane D around toward the stop b, which is rigidly secured to or formed with the upright C, and in thus moving the vane the casing B is also turned, so that the wheel is protected from the wind, as shown in Fig. 3, and hence the wheel is brought to a stop. When the lever I is released, the sleeve E sinks upon the upright and the curved rod F draws the vane D around until it rests against the stop a, extending at about a right angle to the one b, and the casing B is then moved accordingly, so as to allow the wind to strike the wheel and cause it to revolve. The upright C and the casing B are rigidly connected, so that when one turns the other turns with it, and the pressure of the wind against the vane causes the upright and the frame to adjust themselves to every wind that blows.

Having thus described my invention, I claim—

1. In a wind-motor, a suitable supporting-frame, a wheel journaled therein, and a casing composed of two parts which are applied to opposite sides of the wheel, and which are revolvable around the wheel, combined with an upright, which extends above the frame, a vane pivoted to the upright, a sliding collar placed upon the upright, and a curved rod which passes through an eye on the vane,

and by means of which, the vane is moved into, and out of the wind, substantially as shown.

2. In a wind-motor, a suitable supporting frame, a wheel journaled therein, and an upright extending above the top of the frame and provided with two stops for regulating the distance that the vane shall be moved, combined with a vane pivoted or hinged to the upright, a vertically-moving collar placed upon the upright, a lever for moving the collar, and a curved rod which passes through

an eye upon the vane, and by means of which the vane is moved from one stop to the other, the upright being connected with the casing ²⁵ that is applied to the outer sides of the wheel, substantially as described.

In testimony whereof I affix my signature in presence of two witnesses.

EMANUEL D. SCHMUCKER.
